UNITED STATES PATENT OFFICE.

MOSES M. MARCUSE, OF NEW YORK, N. Y., ASSIGNOR TO WEST DISINFECTING COMPANY, OF NEW YORK, N. Y., A CORPORATION OF NEW YORK.

SANITARY CLOSET.

1,297,710.

Specification of Letters Patent. Patented Mar. 18, 1919.

Application filed June 10, 1914. Serial No. 844,207.

To all whom it may concern:

Be it known that I, MOSES M. MARCUSE, a citizen of the United States, and resident of the borough of Manhattan, in the city and State of New York, have invented a new and useful Improvement in Sanitary Closets, of which the following is a specification.

My invention relates to an improvement in sanitary closets, with the following objects in view: providing a novel and sanitary device for receiving the feces and urine, retaining the same for a considerable length of time without creating an offensive odor and concealing from view the receptacle containing the foreign matter under certain conditions; providing means under the control of the person using the closet for automatically agitating the foreign matter in the receptacle; providing means for automatically disintegrating the foreign matter; providing a receptacle for the closet which may be easily removed for cleaning purposes or the contents may be removed while in place; providing a manually operated means for withdrawing the disintegrated foreign matter; providing an overflow for conveying the excess liquid matter away from the receptacle; providing a means for automatically discharging a predetermined amount of a disinfecting and liquefying agent into the receptacle; providing a means for automatically replenishing the container with a disinfecting and liquefying agent to be discharged into the receptacle; providing means for conveying the disintegrated, disinfected and liquefied matter away from the confines of the closet; attaining these sanitary benefits by mechanism capable of easy operation and simple in construction. A practical embodiment of my invention is represented in the accompanying drawings, in which—

Figure 1 represents a sanitary closet, partly broken away to show the parts within in conjunction with the method of treating the deposits usual to the proper use of the closet after it has been discharged therefrom,

Fig. 2 represents a transverse vertical section on a larger scale taken from front to rear showing the parts of the closet in the position they would assume when the person using the same occupies the seat,

Fig. 3 represents a plan view of the same, Fig. 4 represents a transverse section taken in the plane of the line A—A of Fig. 3, several of the parts being broken away to show other parts within,

Fig. 5 represents a transverse section taken in the plane of the line B—B of Fig. 3,

Fig. 6 represents a horizontal section taken in the plane of the line C—C of Fig. 2,

Fig. 7 represents a detail section showing the means of operating the outlet from the deposit receiving receptacle,

Fig. 8 represents a detail horizontal section taken in the plane of the line D—D of Fig. 7,

Fig. 9 represents a detail section of the cover closing device, and

Fig. 10 represents a vertical section of the disinfectant tank with its operating mechanism taken in the plane of the line E—E of Fig. 3.

The casing of the sanitary closet is denoted by 1, its base by 2, a door by 3, which door is hinged at 4 to the casing.

A seat 5 is hinged at 6 to a back member 7, which member is securely fixed to the casing 1 in any well known or approved manner. The seat 5 is provided with a hole 8 of the usual shape.

A cover 9 is provided for closing upon the seat 5, which cover is also hinged at 6 to the back member 7. The cover 9 has secured to its under side an annular gasket 10 of rubber or other material, which is so located as to engage the seat 5 when closed to form a seal between the cover and seat, thereby preventing any odor from escaping between the same. There is located between the seat 5 and the casing 1, a plate 11 having a tubular body 12 depending therefrom, the lower edges of which body are oppositely inclined to form seats for flaps 13, 14. These flaps are fixed to rock shafts 15, 16, mounted in hangers 17, depending from the plate 11 and are arranged to close against the inclined seats and form a bottom for the tubular body.

To operate the flaps 13, 14, I provide plungers 18, 19, arranged to engage arms 20, 21, also fixed to the rock shafts 15, 16, which plungers project upwardly through the plate 11 and are adapted to engage the seat 5 so that when the weight of the person using the closet will be applied to the seat,

the plungers will be forced downwardly, thereby rocking the shafts and opening the flaps. The weight of the seat alone is not sufficient to open the flaps, so I provide that 5 the cover 9, together with the seat 5, will be weight enough to force the plunger down and open the flaps thereby sealing the casting 1 to prevent any odor from escaping at this point when the closet is not in use. The 10 flaps will be closed against their seats by springs 26 mounted on the shafts 15, 16, adapted to engage the flaps, and weights 27 affixed to the outer ends of the flaps. Both the springs and the weights assist in making 15 a tight closure of the flaps against the seats of the tubular body, at the same time lifting the seat by means of the plungers when the cover is raised.

The position of the plungers with respect 20 to the seat is such that it will require the combined weight of both the seat and cover or the weight of a person on the seat to overcome the action of the springs and weights so as to force the flaps to their open 25 position. The front plungers 18 are controlled by the seat 5, and the rear plungers 19 by the cover 9. Thus it will be seen that when the cover is raised from the seat, it takes the additional weight from the seat 30 and the flaps, by means of their springs and weights, immediately close upon the tubular body at the same time lifting the seat and closing the cover, as shown in dotted outline in Fig. 9.

35 The means for automatically closing the cover are constructed, arranged and operated as follows: A push lever 28 having a depending arm 29 is mounted to rock in a bracket 30 secured to the back member 7 with the depending arm 29 passing through 40 a hole 31 in the back member. A rocking lever 32 is mounted to rock in a bracket 33 depending from the back member 7, one end of which lever is adapted to engage an abutment 34 fixed to a flexible connection 35 which passes over a pulley 36 and is attached to the depending arm 29. A weight 37 is secured to the opposite end of the flexible connection 35 for throwing the lever 45 50 28 to its forward position.

A rod 38 hinged at 38° to the seat 5 is provided with nuts 39 adjustable on the rod in position to engage the other end of the rocking lever 32 for lifting the weight from 55 its bracket 40 thereby relieving the tension on the arm 29 and push-lever 28. The parts are so arranged that the push-lever 28 is normally at rest when the cover and seat are closed. The first part of the upward 60 movement of the cover permits the seat to rise, allowing the adjustable nuts 39 on the depending rod 38 to release the lever 32, which, by means of the weight, pulls on the depending arm 29 and forces the push-lever 65 28 forward. The further movement of the

cover forces the lever rearwardly, taking the weight from its seat. The weight being heavier than the cover tends to force it forwardly by means of the push-lever, where, if released, it will fall by gravity to its 70 closed position.

A receptacle 41 is located within the casting 1 and is provided with an upwardly extended bottom 42 having a ridge 43 running from front to rear. The bottom 75 and ridge are slightly inclined so that the liquid deposits falling thereon will pass to the sides and toward the front of the receptacle, into a well 44, from which it may be emptied at any convenient time through the 80 outlet 45.

To disintegrate the deposits within the receptacle, I mount therein, upon opposite sides of the ridge 43, shafts 46, 47, journaled in bearings 48, 49, upon which shafts 85 I secure a series of beaters 50, 51. Some of the beaters are provided with tapered blades 52, so as to beat and break up the solid matter falling upon the bottom 42. The shafts 46, 47, are arranged in parallelism 90 with the bottom so that the beaters will operate equally throughout its length.

A platform 53 provided with openings 55 is located beneath the shaft 46, through which openings, radial prongs 57, fixed to 95 the shaft, are arranged to oscillate. A similar platform 54, having openings 56, is located beneath the shaft 47, through which openings, radial prongs 58, fixed to the shaft 47, are arranged to oscillate. 100

Prongs 59, 60, extend downwardly from the shafts 46, 47, into the chambers formed between the bottom of the receptacle and the platform and serve to agitate the matter therein, while the radial prongs 57, 58, in 105 passing through the openings in the platforms tear and break up any solid matter that falls within their paths.

Guards 61, 62, prevent any solid matter from passing directly into the well 44. 110

The rock-shafts 46, 47, carrying the beaters and agitators, are controlled and operated by the movement of the cover as follows: A swinging stop 63 is mounted on the back member 7 and is linked at 64 to a 115 vertically sliding member 65, which is mounted to slide in bearings in the back member. The lower end of the member 65 is forked, as shown at 66, to receive the connected operating rods 67, 68, which are pivoted to the rock shafts 46, 47, by the lugs 69, 70, fixed thereon.

A pin 71, having a lost motion connection with the stop 63, is mounted in a bracket 72 on the cover 9 and serves to operate the 125 agitators and beaters at each complete upward or downward movement of the cover. The movement of the beaters is controlled by the adjusting nuts 73 on the pin 71, which nuts are adapted to engage the swinging 130

stop 63 as the cover is partly closed upon the seat, while, from this position to the closed position the swinging stop will be rocked forward, thereby lifting the member 65, connecting rods 67, 68, lugs 69, 70, and rocking the shafts 46, 47, that carry the agitators and beaters. Thus it will be seen that upon the opening movement of the cover, the agitators will be raised to the 10 position shown in Fig. 2, by the cover engaging the stop 63, forcing the member 65, connecting rods 67, 68, lugs 69, 70, and rocking the shafts 46, 47. This opening and closing movement of the cover will cause the 15 deposits to become disintegrated and agitated so that they may pass readily into the well 44 and through the outlet 45.

Simultaneously with this agitating and beating, I provide a means for discharging 20 a predetermined amount of disinfecting and liquefying agent into the receptacle so that the deposits therein will be treated with a disinfecting and liquefying agent, while being agitated and disintegrated.

25 The means for discharging this disinfecting and liquefying agent is constructed, arranged and operated as follows: A tank 71 is secured to the casing 1 above the receptacle 41, and has located therein a cylinder 30 72 having a piston 73 and rod 74 fitted to slide in the cylinder. The rod 74 projects upwardly through the tank 71 and back member 7 to a position where it will be engaged by a toe 75 fixed to the cover 9 when 35 in its raised position. A spring 76 is located on the rod 74 between a collar 77 and the tank 71, so as to lift the piston and rod a predetermined distance. An inlet 78, for the disinfecting and liquefying agent, to the 40 cylinder from the tank 71 is located near its bottom and an outlet 79 at the bottom of the cylinder. The outlet 79 is provided with a duct 80 which passes upwardly to the top of the tank 71, terminating in a nozzle 45 so that the discharge therefrom will be directed into the receptacle 41. As the cover 9 is opened to the position shown in Fig. 10, the toe 75 will engage and press downwardly upon the rod and piston, which first cuts 50 off the inlet 78 and then forces the liquid beneath the piston out through the outlet 79 and duct 80 into the receptacle 41. Upon the closing of the cover, the rod being removed, the rod and piston will rise under 55 the tension of the spring until the piston uncovers the inlet, whence the chamber below the piston will be again filled with liquid and ready to discharge the disinfecting and liquefying agent at the next opening of the 60 cover.

The tank 71 may be replenished in the following manner: The tank 71 is provided with a tube 81, which extends a slight distance from the bottom to the upper edges of 65 the back member 7, and has a screw threaded

engagement with an indicator and reservoir 82. This reservoir 82 is provided with a spring pressed ball outlet valve 83 which extends into the tube 81, an inlet 84, a plug 85 for the inlet, and a rod 86 which coacts 70 with the plug and outlet valve. As the plug is removed, the outlet valve closes. When the plug is screwed in, the rod 86 is forced down against the tension of the spring upon the ball valve, thereby opening the same for 75 the liquid to pass into the tank, providing the tank is not filled. The tank is filled by the liquid passing down the overflow tube 87, after the liquid in the reservoir has reached the top of the tube. As the liquid is gradually taken from the tank 71 through the cylinder, so will it gradually be replaced from the reservoir. The reservoir may be made of glass or other suitable material so that it may be readily seen when the tank will require filling as the level of the liquid will fall first in the reservoir.

80 A protector 88 of wire or other suitable material, is secured to the back member 7 and surrounds the reservoir so as to prevent 85 the unintentional displacement of the reservoir from the tank.

85 Where it is desired to convey the disintegrated, disinfected and liquefied matter away from the confines of the closet, I provide a gate valve 89 at the outlet 45 within the well 44, which valve is manually operated by means of a lever 90 pivoted at 91 to the receptacle 41, one end of which lever is connected at 92 to a valve rod 93 fixed to the 90 valve 89. To prevent the valve from being unintentionally left open, I extend the valve rod 93 upwardly a distance where it will extend about the bottom of the seat when the valve is open, so that any weight placed upon 100 the seat while in this position will force the rod and valve down to its closed position, as shown in Figs 2, 4 and 7. The foreign matter passing through the outlet 45 will enter a by-pass having check valves 94, 95, between 105 which check valves is located a manually operated force pump 96, which will force the matter from the by-pass into a rearwardly inclined pipe 97, fixed beneath the receptacle 41. The pipe 97 is coupled to a liquefying tank 98 by a pipe 99. The liquefying tank 98 is provided with an upwardly extending baffle plate 100, a downwardly extending baffle plate 101, and a clean-out flue 102. A basket 103 is lowered through the clean-out 110 flue 102 by means of a wire or rope connected to the cap 104 of the flue, to a position in front of the inlet pipe 99, so that the matter that cannot be liquefied will pass through the opening 105 in the basket 103 and be removed at pleasure.

115 I also propose to insert through the clean-out flue from time to time an additional liquefying, deodorizing and disinfecting agent, to insure a thorough and complete 120 125 130

further treatment of the matter passing into this tank 98 so that it may pass out through the outlet 106 to a predetermined point where it may percolate into the ground.

5 The receptacle 41 is provided with an overflow pipe 107 which leads directly into the pipe 97. The top of this pipe 107 is provided with wires 108 to prevent paper or other matter passing thereinto and clogging 10 the same.

To carry off all odors within the casing 1, I arrange a series of holes 109 near the bottom, which, together with a ventilating pipe 110 situated in the back member 7, tends to 15 induce a current of air to pass upwardly through the casing and out through the ventilating pipe 110.

I wish it to be understood that the plate 11, with the parts carried thereby, may be 20 removed at pleasure.

It is evident that changes may be resorted to in the form, construction and arrangement of the several parts without departing from the spirit and scope of my invention; 25 hence I do not wish to limit myself strictly to the structure herein set forth, but

What I claim is:—

1. A sanitary closet receptacle having a well therein, a ridged and inclined bottom 30 leading to said well, an outlet for said well, and means for opening and closing said outlet.

2. A sanitary closet receptacle having a well therein, a ridged and inclined bottom 35 leading to said well, an outlet for said well, and a valve for opening and closing said outlet.

3. A sanitary closet receptacle having a well therein, a ridged and inclined bottom 40 leading to said well, an outlet for said well, a valve for opening and closing said outlet, and means within the receptacle for disintegrating and agitating the deposits for the passage thereof through said outlet.

45 4. A sanitary closet receptacle having a well therein, a ridged and inclined bottom leading to said well, an outlet for the well, a valve for opening and closing said outlet, and a pump connected to said outlet for 50 forcing the deposits away from the outlet.

5. A sanitary closet receptacle having a well therein, a ridged and inclined bottom leading to said well, an outlet for said well, a valve for opening and closing said outlet, 55 a pump connected to said outlet for forcing the deposits away from said outlet, and a check valve located between said pump and outlet.

6. A sanitary closet receptacle having a 60 well therein, a ridged and inclined bottom leading to said well, an outlet for said well, a valve for opening and closing said outlet, a pump connected to said outlet for forcing the deposits away from said outlet, and check

valves located upon opposite sides of the 65 pump.

7. A sanitary closet receptacle having a well therein, a ridged and inclined bottom leading to said well, an outlet for said well, a valve for opening and closing said outlet, 70 means within the receptacle for disintegrating and agitating the deposits for the passage through said outlet, a pump connected to said outlet for forcing the deposits away from the outlet, and check valves located 75 upon opposite sides of the pump.

8. A sanitary closet comprising a casing, a seat therefor, a cover for said seat, a receptacle within said casing for receiving the deposits usual to the proper use thereof, 80 said receptacle having a well therein, a ridged and inclined bottom leading to said well, an outlet for the well, a valve for said outlet and a pump connected to said outlet for forcing the deposits away from the out- 85 let.

9. A sanitary closet comprising a casing, a seat therefor, a cover for said seat, a receptacle within said casing for receiving the deposits usual to the proper use thereof, 90 said receptacle having a well therein, a ridged and inclined bottom leading to said well, an outlet for the well, a valve for said outlet, means operated by the cover for disintegrating and agitating the deposits, said 95 means comprising shafts mounted in the receptacle and having a series of beaters and prongs adapted to be oscillated by the movement of the cover, platforms having openings in position to coat with said prongs, 100 a pump connected to said outlet for forcing the deposits away from the outlet, and check valves located upon opposite sides of the pump.

10. A sanitary closet comprising a casing, 105 a seat therefor, a cover for said seat, a disinfecting and liquefying device, a receptacle within said casing for receiving the deposits usual to the proper use thereof, said receptacle having a well therein, a ridged 110 and inclined bottom leading to said well, an outlet for the well, a valve for said outlet, and a pump connected to said outlet for forcing the deposits away from the outlet.

11. A sanitary closet comprising a casing, 115 a seat therefor, a cover for said seat, a disinfecting and liquefying device operated by said cover, a receptacle within said casing for receiving the deposits usual to the proper use thereof, said receptacle having a well 120 therein, a ridged and inclined bottom leading to said well, an outlet for the well, a valve for said outlet, and a pump connected to said outlet for forcing the deposits away from the outlet.

12. In sewage disposal apparatus, the combination of a hopper, a cover therefor, a tank into which the hopper discharges, a

movable agitator in the tank, and operative connections between the agitator and the said cover whereby when the cover is raised the agitator is moved out of the way of entering matters and when the cover is lowered the agitator is caused to submerge such matters.

In testimony, that I claim the foregoing as

my invention, I have signed my name in presence of two witnesses, this twenty-second day of May, 1914.

MOSES M. MARCUSE.
